UNITED STATES PATENT OFFICE.

CHARLES S. NELSON, OF COCOLALLA, IDAHO, ASSIGNOR OF ONE-HALF TO WILLIAM E. JAEGER, OF SANDPOINT, IDAHO.

VACUUM TANK.

Application filed February 14, 1925. Serial No. 9,311.

To all whom it may concern:

Be it known that I, CHARLES S. NELSON, a citizen of the United States, residing at Cocolalla, in Bonner County and State of Idaho, have invented certain new and useful Improvements in Vacuum Tanks, of which the following is a specification.

The present invention relates to improvements in vacuum tanks of that type having a float control and maintained oil level for use in liquid fuel feeding systems of internal combustion engines for automobiles, and for illuminating and heating burners and other similar appliances.

15 The primary object of the invention is the provision of a device of this character which is simple in construction and operation, and in which the parts are compactly arranged in such manner as to assure reliability and efficiency in the operation of the vacuum tank and gasoline or oil feeding system. By the utilization of my invention a uniform and regulated feed of the gasoline is automatically accomplished.

20 25 The invention consists in certain novel combinations and arrangements of the control or operating parts as will hereinafter be more fully set forth and claimed.

In the accompanying drawings I have 30 illustrated one complete example of the physical embodiment of my invention wherein the parts are combined and arranged in accordance with the best mode I have thus far devised for the practical application of the principles of my invention.

The figure of drawing illustrates graphically a vertical section of the appliance and shows the relation of parts.

In carrying out my invention I utilize a 40 main feed tank indicated as a whole by the numeral 1 and preferably of cylindrical shape. Within the main tank the gasoline receiving or vacuum 2 is supported at its upper end, a flanged top 1^a for the main tank being secured as by bolts 2^a to the flanged top of the vacuum tank, with packing or gaskets for affording a liquid and air tight joint.

The inlet or supply pipe 3 opens through 50 the top or lid of the main tank and communicates with the usual gasoline supply tank not shown, and the suction or vacuum pipe 4 which enters the main tank top communicates with the intake manifold of the inter-

nal combustion for withdrawing pressure 55 from the vacuum tank in usual manner.

A vent tube 5 is provided for the vacuum tank and is supported in the top of the main tank to prevent overflow of gasoline when the supply tank is elevated higher 60 than the vent tube, as when an automobile is descending a hill or steep grade. The gasoline is permitted to flow to the carburetor, not shown, through the feed pipe 6 leading from the bottom of the main feed tank, and 65 the usual screen 6' is provided within the main tank for this outlet pipe.

The vent tube opening and the vacuum pipe opening are controlled by the position of a single float 7 in the vacuum tank. This 70 float is carried on the stem 8 and is capable of vertical motion with relation to the stem between the upper stop 9 and the lower stop 10 of the stem. The stem is pivoted at 11 on the arm 12 of the vacuum control lever which governs the flow of gasoline into the main tank from the supply tank. This lever has three arms 13 14 and 15 and is pivoted at 16 or suspended within the vacuum tank 75 from the bracket 17 attached at the inner side of the lid or top 1^a.

The lever is provided with a snap action by the use of the spring 18 having its ends anchored to the bracket and to the end of the arm 15 of the lever. Thus with the 80 vacuum tank open to the engine cylinder and to the supply tank as shown, when the float is elevated to the proper level the lever is actuated with a snap action. The float rises with relation to the stem until it 85 strikes the stop 9 then continued movement of the float causes the stem to swing the lever on its pivot sufficiently for the spring to swing across the pivot 16 whereupon the lever is actuated with the spring action. 90 A downward movement of the float is performed in a reverse operation and the lever is snapped into action by the reverse movement of the spring.

The lever arm 13 carries at its free end a 100 ball valve 19 for closing the vent or valve-seat 20 of the vent tube as shown.

A similar ball valve or suction valve 21 is carried at the opposite end of the lever arm 14 and adapted to close the suction valve 105 seat 22. When the vent valve is open the suction valve is closed and vice versa, and these valves are automatically actuated by

the controlling float to maintain the required gasoline level in the vacuum tank.

Admission of gasoline from the vacuum tank to the main feed tank is permitted 5 through the valved seat or port 23 located in the bottom of the vacuum tank, and a ball valve 24 in the feed tank 1 controls this flow of gasoline from one tank to the other.

The feed valve 24 is under control of a 10 float 25 in the feed tank which co-operates with a bell crank lever 26 that also has a snap action. The lever is pivoted on a bracket 27 in the feed tank and supported from the bottom of the vacuum tank, and 15 the spring 28 snaps the lever to open or close the feed valve due to the action of the float.

The appliance is equipped with the usual accessories as a priming cup and valve 29 carried by the top 1^a and opening into the 20 vacuum tank, a drain cock 30 for the feed tank, and a vent or overflow pipe 31 communicating with the top or upper portion of the feed tank and extending up alongside the tank to near the top of the vacuum tank.

25 The port 23 is comparatively large to permit a quick flow of gasoline from the vacuum tank to the feed tank and the vent pipe 31 permits atmospheric pressure in the feed tank to insure flow of gasoline therefrom to 30 the carbureter. The float automatically

controls the admission of gasoline to the feed tank and the valve 24 is closed with a snap action by the overbalanced spring 28 when the proper level is reached.

Thus the two floats by their movement 35 automatically control suction from the vacuum tank and feed of gasoline to the vacuum tank, and admission of gasoline from the vacuum tank to the feed tank respectively, the feed tank being at all times in communication with the carbureter. 40

Having thus fully described my invention what I claim as new and desire to secure by Letters Patent is—

In a vacuum tank provided with spaced suction and vent ports in the top thereof, a bracket depending from the tank top between said ports, a three arm lever pivoted on said bracket, two arms of said lever extending oppositely from one end thereof and having balls formed on the ends thereof for closing said ports, a snap throw spring extending between said bracket and the end of the third lever arm, said last named arm having an arm extending laterally therefrom, and a float carrying stem pivoted on the outer end of said laterally extending arm for control of said lever movement. 50 55

In testimony whereof I affix my signature.
CHARLES S. NELSON.
